UNITED STATES PATENT OFFICE.

RICHARD THEW, OF CLEVELAND, OHIO.

MACHINE FOR HANDLING COAL, ORE, &c.

SPECIFICATION forming part of Letters Patent No. 593,062, dated November 2, 1897.

Application filed August 17, 1896. Serial No. 603,071. (No model.)

To all whom it may concern:

Be it known that I, RICHARD THEW, a citizen of the United States, residing at Cleveland, in the county of Cuyahoga and State of Ohio, have invented certain new and useful Improvements in Machines for Handling Coal, Ore, &c.; and I do hereby declare the following to be a full, clear, and exact description of the invention, such as will enable others skilled in the art to which it appertains to make and use the same.

My invention relates to improvements in machines for handling coal, ore, and other material on docks, in railway yards, and other places.

The invention is, in a sense, an improvement in the class of machines shown and described in certain prior patents granted to me—to wit, No. 436,928, dated September 23, 1890, and No. 553,082, dated January 14, 1896—since it, like them, includes a movable trolley, a sweep-arm pivoted thereto, a bucket, scoop, or shovel carried by said arm, and mechanism for operating said sweep-arm and trolley. The machine hereinafter described embodying my invention is, however, a traction-machine, having power to propel itself from place to place independently of any tracks or guideways, and the invention in part resides in the mechanism for effecting this result.

Other parts of the invention relate to other parts of the machine and are not necessarily confined in their use to such a traction-machine; and the invention consists in the construction and combination of parts, as hereinafter described, all of which is pointed out definitely in the claims.

In the drawings, Figure 1 is a perspective view of a machine embodying my invention. Fig. 2 is a bottom plan view of the traction mechanism. Fig. 3 is a sectional front view on line 3 3 of Fig. 2. Fig. 4 is a sectional side view of the fifth-wheel mechanism. Fig. 5 is front view of the trolley and its supports; and Fig. 6 is a side view, partly in section, of the mechanism for moving the trolley.

Referring to the parts by letters, A represents the truck, which may be of any suitable construction. As shown, this truck consists of two flanged beams *a a*, forming the sides, a cast frame *a'*, which lies between and

is bolted to the said beams, and one or more transverse beams *a''*. Secured by bolts upon and supported by the truck is a circular casting *F*, having an annular channel *f* in its top surface and a circular rack *f'* on its periphery. The truck is supported on wheels *C C' C'' C'''*. The rear wheels *C C'* are independently mounted on an axle *c'*, which is secured to the truck-beams *a a* by means of brackets *c''*. The front wheels *C'' C'''* are mounted on an axle *c''*, which is connected with the truck by any suitable fifth-wheel contrivance—as, for example, that shown in Fig. 2, in which *E* represents a king-bolt which is mounted in bearings in the brackets *a'' a'''*, which are secured to the front end of the truck. The king-bolt has a yoke *e* near its middle, through which the front axle passes and to which it is pivoted on a pin *e'*.

A base *B* supports the motor and other mechanism driven thereby, which I will presently explain. This base may consist of two side flanged beams *b b*, suitably connected together, and a casting *b'*, lying between said beams and bolted or otherwise secured thereto. This casting has on its under side an annular groove *b''* of the same diameter as the similar groove *f*, and the entire base is supported on a row of balls *H*, which run in the raceway formed by the two annular grooves *b''* and *f*.

A vertical sleeve *I* passes through the platform-casting *b'* and the truck-casting *a'* at the center of the annular grooves *f* and *b''*, and this sleeve is bolted to the truck-casting *a'*. This sleeve serves as the pivot of the base *B*, and it also furnishes a bearing for the hollow shaft *J*, which passes through it and serves as the means for transmitting power from the mechanism on the base to the mechanism suspended from the truck. This shaft *J* may have the gear *j''* secured to its upper end, whereby the shaft may be revolved by a suitable motor on the base.

A motor of some sort is mounted upon the base *B*, and suitable intermediate mechanism for connecting the motor to the several shafts, which are shown and described, must be provided, but no attempt has been made to show in detail the motor or such connecting mechanism.

Mounted in suitable bearings on the base

and extending from the upper to the lower side thereof is a shaft K, having on its lower end a pinion k , which engages with the rack f' . As the shaft K is turned by the motor 5 and connecting mechanism the base B is revolved about its axis upon the balls H.

Mounted in brackets $d' d'$ on the under side of the truck is a shaft D, and a bevel-gear d , which is fixed to said shaft D, meshes with a bevel-gear j on the lower end of shaft J. A gear d^2 is also secured to said shaft D, and it meshes with a gear G, the hub of which embraces and is loosely mounted upon the adjacent ends of the two shafts M and M'. 15 These shafts are mounted in brackets $m^2 m^3$, which are secured to the under side of the truck.

Two bevel-gears $g g$ are mounted on the gear G on radial axes, and said gears project 20 from both sides of said gear G. The bevel-gears $m' m'$, which are keyed, respectively, to the shafts M M', mesh with both of these gears $g g$ on opposite sides of their own centers. The sprocket-wheels $m^4 m^5$ are keyed, 25 respectively, to the two shafts M M'. Sprocket-wheels $C^5 C^6$ are fixed, respectively, to the rear wheels C C', and chains $C^7 C^8$ (indicated by dotted lines in Fig. 2) connect the sprocket-wheels $C^5 C^6$ with the sprocket-wheels $m^4 m^5$, 30 whereby motion from the shafts M M' is transmitted to the wheels C C'. If when the gear G is revolved the resistance to the rotation of both rear wheels is substantially equal, the bevel-gears $g g$ will not revolve upon 35 their axes, wherefore both shafts M M' will be revolved equally in the same direction and so will both wheels C C'; but when the resistance to the rotation of said wheels is unequal the gears $g g$ will be revolved upon

40 their axes in one direction or the other, and consequently the shafts M M' will be revolved at unequal speeds. For example, if the wheel C is absolutely prevented from revolving, the shaft M and gear m cannot revolve, 45 wherefore the revolution of the gear G will cause the gears $g g$ to be revolved through their engagement with the then stationary gear m . The gear m' is therefore revolved at an increased speed, due in part directly to 50 the rotation of the gear G and in part to the rotation of the gear g . This compensation-gearing last described acts automatically when the front wheels are turned to one side or the other and causes that rear wheel 55 which is on the outside of the curve to revolve proportionately faster than the other rear wheel.

On the top of the platform B are secured the two upright side frames T, having cantilever extensions t . These side frames are connected by transverse overhead bars t' , and they support the rails S on which the trolley R runs. The trolley may have the grooves r in its sides, which receive the rails, whereby 60 it may slide backward and forward upon the rails, or it may be of any other construction 65

adapted to be moved backward and forward upon the said rails.

The sweep-arm P is pivoted to the trolley in the usual or any appropriate manner. On its lower end is a bucket, scoop, or shovel p , which is preferably adapted to automatically scoop up the material to be handled. The sweep-arm is moved by means of the tackle-cable O, which passes through the pulley-blocks 70 o q on the said sweep and on the end of an inclined overhanging derrick-arm Q, respectively. The cable is taken in or paid out by a winding-drum o^2 on the platform, which is operated by suitable connection with the 75 motor.

The trolley is caused to traverse the track backward and forward by means of a screw V, which is secured to the trolley. A nut v' , mounted on the screw between two fixed 80 shoulders $v^2 v^3$, prevents it from moving endwise. This nut has sprocket-teeth v^4 upon its outer periphery, and it is driven by a chain v^6 , which connects it with a sprocket-wheel v^5 on a driven shaft v^7 .

Extending down through the hollow shaft J is a shaft X, having a hand-wheel x' or other means for turning it upon its upper end. On its lower end is a worm-screw x^2 , which engages with a worm-wheel y , which is secured 90 to the shaft Y. This shaft is mounted in depending brackets $y' y'$ on the under side of the truck, and the two drums $y^2 y^3$ are secured to said shaft. The chains $y^4 y^5$, which are secured to the front axle on opposite sides 100 of the fifth-wheel, are wound in opposite directions upon said drums, respectively. Therefore by turning the shaft X the front axle may be turned so as to guide the movement of said machine.

The described machine is entirely self-contained, carrying its own motor. It may move from place to place and into proper relation to the pile of ore, coal, or other material to be handled. Then by operating the trolley 110 and sweep-arm by means of the described mechanism the material is shoveled up by the scoop. The platform B may then be turned upon its axis, whereby, together with the movement of the trolley and sweep-arm, 115 the scoop or bucket may be carried near any desired point, as a car or hatchway, and dumped.

By the proper operation of the described machine a surface may be cleaned with approximately the same completeness as could be done by men with shovels.

Having described my invention, I claim—

1. In a machine for handling coal, ore, &c., the combination of a traction-carriage, a rotatable platform mounted thereon, upright track-frames secured to said platform and supporting elevated tracks, a trolley movable thereon, a depending sweep-arm pivoted to the trolley, and a feed-screw rigidly fixed to 125 said trolley, with a nut on said feed-screw having sprocket-teeth on its periphery, fixed 130

shoulders engaging on both sides of said nut preventing its longitudinal movement, a driven sprocket-wheel, and a chain running over said sprocket-wheel and nut transmitting motion from the one to the other, substantially as and for the purpose specified.

5 2. In a machine for handling coal, ore, &c., the combination of a wheel-truck, a revoluble platform pivoted thereon, two upright frames secured on said platform, united at their upper ends, and having each a cantaliver extension, tracks mounted on said frames, a trolley movable upon said tracks, a depending sweep-arm pivoted to said trolley, a derrick-arm fixed to the platform and overhanging said cantaliver extensions, a winding-drum on the platform, a sheave on said derrick-arm, an operating-cable connected with said sweep-arm and winding-drum and passing over said sheave, platform-turning mechanism and trolley-actuating mechanism, substantially as and for the purpose specified.

20 3. In a machine for handling coal, ore, &c., the combination of a truck consisting of side-bars, and a casting lying between and secured to said side-bars, an annular casting secured on said truck having an endless ball-groove in its top side, a platform having an annular ball-groove on its under side, balls in said grooves between said platform and annular casting, a sleeve passing through the truck-casting having an annular flange which rests upon and is bolted to said truck-casting, and extends up through a hole in the platform, a shaft mounted in and passing through said sleeve, and serving as the means for transmitting motion from mechanism on the platform to mechanism suspended from the truck, substantially as and for the purpose specified.

25 4. In a machine for handling coal, ore, &c., the combination of a wheel-truck, and a king-bolt for connecting the front axle to the truck, mechanism for turning the axle upon said king-bolt, a revoluble platform mounted on the truck, a sleeve passing axially through the platform and truck and secured to one of them, a hollow shaft mounted in and extending through said sleeve, a shaft mounted in and extending through said hollow shaft, and mechanism connecting said inner shaft with the mechanism for turning the axle upon the king-bolt, substantially as and for the purpose specified.

30 5. In a machine for handling coal, ore, &c., the combination of a wheel-truck, a revoluble

platform mounted thereon, a sleeve passing through both parts named and secured to one of them, a hollow shaft mounted in and passing through said sleeve, a gear on the lower end of said shaft, a shaft mounted in brackets suspended from the truck, a gear secured thereto in mesh with the gear last named, mechanism transmitting motion from said last-named shaft to the rear driving-wheels, a vertical shaft passing through said hollow shaft, a drum-shaft, drums thereon, the front axle, a king-bolt connecting the front axle with the truck, chains connecting said axle with the drum-shaft, and mechanism intermediate of said vertical shaft and drum-shaft, substantially as and for the purpose specified.

35 6. In a machine for handling coal, ore, &c., the combination of a wheel-truck, a revoluble platform mounted thereon, the front axle, a king-bolt connecting the same with the truck, a vertical shaft passing through the platform and truck at the axis of the platform, a worm on the lower end of said shaft, a worm-wheel mounted below the truck receiving motion from said worm, a drum-shaft receiving motion from said worm-wheel, two drums thereon, and two chains wound in opposite directions upon said drums and connected with said front axle, substantially as and for the purpose specified.

40 7. In a machine of the character described, the combination of a wheel-truck, a revoluble platform mounted thereon, a vertical shaft extending axially through said platform and through said truck for transmitting motion from mechanism on the platform to mechanism suspended from the truck, two independent shafts M M' mounted in the same axial line in brackets suspended from the truck, two bevel-gears secured respectively to said shafts, a wheel G mounted between said bevel-gears in the same axial line, a bevel-gear mounted on said wheel in mesh with said two bevel-gears, its axis being radial with respect to said wheel, two independent driving-wheels, sprocket-wheels fixed to said driving-wheels and shafts M M' respectively, and two sprocket-chains, and mechanism connecting said wheel G and vertical shaft, substantially as and for the purpose specified.

45 In testimony whereof I affix my signature in presence of two witnesses.

RICHARD THEW.
